UNITED STATES PATENT OFFICE

2,461,176

MULLING APPARATUS

Walter F. Piper, Chicago, Ill., assignor, by mesne assignments, to Pettibone Mulliken Corporation, a corporation of Delaware

Application June 30, 1945, Serial No. 602,564

5 Claims. (Cl. 241—124)

1

The present invention relates generally to mulling apparatus. More particularly the invention relates to that type of apparatus which is designed and adapted to mull material, such, for example, as molding sand in order properly to condition it preparatory to use, and as its main components or parts comprises: (1) a bowl-shaped receptacle which is adapted to receive and retain a batch of the material to be mulled; (2) a rotary horizontally extending crosshead which is disposed in, and extends across, the central portion of the receptacle, is supported from above and is connected for drive by an electric motor through the medium of speed reducing gearing; (3) a rotary mulling wheel which is carried by the crosshead and is adapted in connection with drive of the latter to travel in a circular path around the receptacle and effect mulling of the material by squeezing it against the receptacle; and (4) a plow which is supported by the crosshead so that it overlies the receptacle bottom, and operates during drive of the crosshead to plow the material in the receptacle and deflect it into the path of the rotary mulling wheel.

In a mulling apparatus of this type it has heretofore been proposed to utilize a standard or conventional plow as the medium for plowing the material in the receptacle and deflecting it into the path of the mulling wheel. With such a plow the apparatus has proved in practice to be highly inefficient and defective because of the fact that the plow in connection with drive of the crosshead does not operate on, or effect plowing of, the portion of the material in the central part of the receptacle and hence the batch of material after a mulling operation is not homogeneously and properly mulled.

One object of the invention is to provide a mulling apparatus of the type under consideration which is an improvement upon and eliminates the defects of previously designed apparatus of the same general character by reason of the fact that the plow is so designed and constructed that it operates on, and serves to plow outwards, the material in the central portion of the receptacle as well as the remainder of the material to the end that the entire batch of material is mulled in a thorough and efficient manner.

Another object of the invention is to provide a mulling apparatus of the last mentioned character in which the plow is of spiral contour or configuration and has the inner end thereof in substantial alignment with the center or axis of the receptacle.

2

Another object of the invention is to provide in connection with a mulling apparatus of the aforementioned type and character novel means whereby the plow is so connected to the rotary horizontally extending crosshead that it may be adjusted not only vertically but also in a tilted manner to the end that the lower edge may be brought as close as possible to the bottom of the receptacle.

10 A further object of the invention is to provide a mulling apparatus of the type under consideration in which the crosshead is of new and improved design and the rotary mulling wheel is connected to the crosshead in a novel and efficient manner.

15 A still further object of the invention is to provide a mulling apparatus which is generally of new and improved construction, effectively and efficiently fulfills its intended purpose, is so designed and constructed that it may be produced at a comparatively low and reasonable cost, and is an improvement upon, and has certain inherent advantages over, the mulling apparatus forming the subject matter of application for letters patent filed April 24, 1944 and serially Numbered 532,445, now Patent No. 2,450,299, Sept. 28, 1948.

20 Other objects of the invention and the various advantages and characteristics of the present 25 mulling apparatus will be apparent from a consideration of the following detailed description.

25 The invention consists in the several novel features which are hereinafter set forth and are more particularly defined by claims at the conclusion hereof.

30 In the drawings which accompany and form a part of this specification or disclosure and in which like numerals of reference denote corresponding parts throughout the several views:

35 40 Figure 1 is a vertical section of a mulling apparatus embodying the invention;

45 Figure 2 is a horizontal section taken on the line 2—2 of Figure 1 and illustrating in detail the construction, arrangement and design of the plow for plowing and deflecting the material to be mulled in connection with a mulling operation; and

50 Figure 3 is a perspective of the plow and crosshead.

55 The apparatus which is shown in the drawings constitutes the preferred form or embodiment of the invention. It serves as a medium for mulling material such as molding sand in a foundry in order properly to condition it preparatory to use, and as its principal or primary components com-

prises a receptacle 5, a rotary horizontally extending crosshead 6, a pair of mulling wheels 7, and a plow 8.

The receptacle 5 is adapted to be charged with a batch of material to be mulled and consists of a lower section 9 and an upper section 10. The lower section comprises a circular bottom wall 11 and an upstanding cylindrical side wall 12 and forms a part of a wheelbarrow 13 whereby it may be wheeled or transported from place to place. The bottom wall 11 is formed of plate metal and defines or constitutes the bottom of the receptacle 5. The cylindrical side wall 12 is formed integrally with, and projects upwards from, the marginal portion of the bottom wall 11 and has its upper end reenforced by an externally disposed angle bar type ring 14. The upper section 10 of the receptacle 5 is in the form of a cylindrical side wall 15 and this is the same in diameter as the side wall 12 and is adapted to rest on, and form a continuation of, the latter in connection with use of the apparatus. When the side wall 15 is in its operative position wherein it rests on the side wall 12 of the lower section 9, as shown in Figure 1, it forms with said side wall the side wall of the receptacle. The lower end of the side wall 15 is reenforced by an externally disposed angle bar type ring 16 and the upper end of said side wall is reenforced by an externally disposed angle bar type ring 17. Two laterally spaced parallel horizontal angle bars 18 extend across the upper end of the side wall 15 constituting the upper section of the receptacle 5 and form with a bail 19 a medium or instrumentality whereby the upper section 10 of the receptacle may be raised and lowered with respect to the lower section 9. The ends of the angle bars 18 rest upon and are welded or otherwise fixedly secured to the reenforcing ring 17 at the upper end of the cylindrical side wall 15. The bail 19 is adapted to be attached to the hook of an overhead crane (not shown) and has the lower ends of its legs positioned in straddled relation with, and fixedly connected to, the central portions of the angle bars 18. In connection with use of the apparatus it is contemplated that the lower section 9 of the receptacle will be filled with a batch of the material to be mulled and then the wheelbarrow 13 of which the lower section of the receptacle forms a part, will be wheeled under the upper section 10 of the receptacle. After the wheelbarrow is wheeled under the upper section 10 it is released by the operator so that the legs thereof rest on the floor. Thereafter the upper section 10 is lowered by proper manipulation of the overhead crane until the reenforcing ring 16 is in registry with, and rests on, the reenforcing ring 14. After a mulling operation the upper section of the receptacle is raised by the overhead crane and the wheelbarrow 13 is then wheeled to the location where the mulled material is to be used. Depending guide fingers or other suitable means (not shown) on the lower end of the side wall 15 serve to hold the upper section 10 of the receptacle against lateral displacement with respect to the lower section 9 when the two sections are in their operative position wherein the upper section rests on, and is supported by, the lower section and its side wall 15 forms with the side wall 12 of the lower section the side wall of the receptacle as a whole.

The crosshead 6 is disposed within, and extends radially with respect to, the cylindrical side wall 15 constituting the upper section 10

of the receptacle. It supports the mulling wheels 7 and the plow 8 as hereinafter described and consists of a block-like inner member 20 and an elongated arm-like outer member 21. The inner member is provided with a vertically extending screw threaded bore 22 and is welded or otherwise fixedly secured to the inner end of the outer member 21. The latter is channel spaced in cross section and consists of a horizontally extending web 23 and a pair of laterally spaced depending side flanges 24. As shown in the drawings, the side flanges are formed integrally with, and project downwards from, the side margins of the horizontally extending web 23. The block-like inner member 20 is arranged so that the axis of its bore is aligned with the vertical axis of the cylindrical side wall 15 constituting the upper section 10 of the receptacle, and the outer end of the elongated outer member 21 terminates inwards of the inner periphery of said side wall 15. The crosshead 6 is fixedly connected to the lower end of, and is driven by, a vertically extending drive shaft 25 which, in turn, is driven by a unidirectional electric motor 26 through the medium of speed reducing gearing 27 in a housing 28. The lower end of the drive shaft is provided with an externally threaded stem 29 and this extends through and is in interlocked relation with the vertically extending screw threaded bore 22 in the blocklike inner member 20 of the crosshead. The central portion of the drive shaft 25 is journalled in a bearing 30 on the bottom of the housing 28 and the upper end of the drive shaft projects into the housing interior. Said housing 28 is mounted on, and fixedly secured to, the central portions of the angle bars 18 which, as previously pointed out, extend across the upper end of the side wall 15. The electric motor 26 is mounted on top of the housing 28 and is arranged so that the armature shaft extends vertically. The lower end of the armature shaft extends into the upper portion of the interior of the housing 28 and is operatively or drivably connected to the drive shaft 25 by way of the speed reducing gearing 27. When the electric motor 26 is in operation it operates to drive or rotate the crosshead 6 and the latter, in turn, causes the mulling wheels 7 and the plow 8 to travel in a circular course around the bottom wall 11 of the lower section 9 of the receptacle and thus effect mulling of the batch of the material in the receptacle.

The two mulling wheels 7 are located at opposite sides of the crosshead 6 and are adapted in connection with a mulling operation, i. e., when the receptacle 5 is charged with a batch of material, to travel in a circular course over the downwardly dished bottom wall 11 of the lower section of the receptacle and effect mulling of the material by squeezing it against said bottom wall. They comprise disc-like bodies 31 and rubber tires 32 around the bodies and are rotatably mounted on the ends of an axle 33 which underlies the drive shaft 25 and extends at right angles to the crosshead 6. The central portion of the axle 33 is welded to one end of a substantially horizontal arm 34. The latter, as best shown in Figure 1, is spaced beneath and in parallel relation with the crosshead 6. The other end of the arm 34 fits between the central portions of the depending side flanges 24 of the outer member of the crosshead and has welded to its under side a tubular pivot element 35. A pivot bolt 36 extends through aligned holes in the lower central portions of the depending side flanges 24 and

also through the tubular pivot element 35 and forms with said element a pivotal connection whereby the arm 34 and the axle 33 together with the two mulling wheels are permitted to swing vertically to a limited extent. A substantially vertically extending bolt 37 extends through a hole 38 in the central portion of the arm 34 and a vertically aligned hole 39 in the horizontally extending web 23 of the outer member of the crosshead and serves to limit downward swinging of the wheels 7. This bolt is arranged so that the head thereof is at the bottom and has a pair of nuts 40 on the upper end of its shank. By adjusting the nuts on the shank of the bolt 37 the amount of downward swinging movement of the wheels with respect to the crosshead may be varied. The uppermost nut serves as a lock nut. In order to urge the mulling wheels 7 downwards a spiral compression spring 41 is provided. This spring surrounds the shank of the bolt 38 and is arranged so that the lower end thereof abuts against the central portion of the arm 34 and its upper end abuts against the portion of the web 23 that defines the hole 39. When the upper section 10 of the receptacle is raised with respect to the lower section the arm 34 swings relatively to the crosshead until it rests on the head of the bolt 38. At such time the arm is in fixed relation with the crosshead and as a result in connection with additional upward movement of the upper section of the receptacle the mulling wheels move upwards. When the upper section of the receptacle is lowered into its operative position with respect to the lower section the mulling wheels, after being brought into engagement with the circular bottom wall 11, cause the arm 34 to swing upwards to a limited extent with respect to the crosshead. When the two sections of the receptacle are in position for a mulling operation the spiral compression springs 41 exerts downward pressure on the mulling wheels 7 with the result that the wheels in connection with travel over the bottom wall 11 effect the desired squeezing and resultant mulling of the material. By reason of the fact that the compression spring 41 is disposed between the depending side flanges 24 of the outer member of the crosshead it is effectively housed against contact with the material in connection with a mulling operation.

The plow 8 is connected to, and driven conjointly with, the crosshead 6 and serves during a mulling operation to plow all of the material in the receptacle 5 and also to direct the material into the path of the two mulling wheels 7. It is spiral so far as contour or configuration is concerned, directly overlies the bottom wall 11 of the lower section 9 of the receptacle when the upper and lower receptacle sections are in their operative position, and consists of an inner part 42 and an outer part 43. An L-shaped bar 44 serves to connect the plow to the crosshead. Such bar is preferably formed of comparatively heavy metal stock, is square in cross section and consists of a vertically extending piece 45 and a horizontally extending piece 46. The later piece is formed integrally with the lower end of, and extends at right angles to, the vertically extending piece 45. The inner part 42 of the plow 8 is approximately the same in height as the cylindrical side wall 12 of the lower section of the receptacle 5. It is formed of heavy plate metal and is so positioned that the leading edge thereof is in true alignment with the longitudinal center of the receptacle. As indicated by the arrow in Figure 2, the crosshead of the apparatus is driven in a clockwise direction

when viewed from above. From its leading edge the inner part 42 of the plow extends outwards and is curved in a counterclockwise fashion. The outer part 43 of the plow is approximately half as high as the inner part and has its inner end welded or otherwise fixedly secured to the outer lower corner of the inner part 42. The outer end of the outer part terminates directly inwards of the side wall 11 of the lower section 9 of the receptacle. The outer plow part, like the inner part, is formed of heavy plate metal. The plow so far as curvature is concerned, progressively and substantially uniformly increases in radius from the inner or leading edge of the inner part 42 to the outer end edge of the outer part 43. The bottom edge of the plow is shaped conformably to the circular downwardly dished bottom wall 11 of the lower section of the receptacle. As the result of the arrangement and design of the plow 8 the portion of the material which finds its way to the center of the receptacle during a mulling operation comes in contact with the leading edge of the inner part of the plow and is caused positively to move outwards past the outer face of the plow and towards the cylindrical side wall 11 of the lower receptacle section. After passing the inner part of the plow some of the material of the batch to be mulled is flung outwards against the side wall 11 and the balance or remainder passes over the outer part of the plow. By reason of the fact that it is impossible for any of the material to collect in the center of the receptacle the entire batch of material is subject to effective plowing on the part of the plow and is ultimately guided into the path of the mulling wheels to the end that the batch as a whole is homogeneously mulled. The plow is arranged so that the outer part 43 thereof is disposed substantially midway between the two mulling wheels 7. The horizontally extending piece 46 of the bar 44 extends at right angles to the crosshead 6 and has the outer end thereof welded to the trailing marginal portion of the inner part 42 of the plow at a point directly above the inner end of the outer plow part 43. An elongated horizontally extending bracket plate 47 extends between and is welded to the upper inner corner of the inner plow part 42 and the lower end of the vertically extending piece 45 of the bar. The upper end of said vertically extending piece 45 is disposed outwards of, and in substantially parallel relation with, a vertically extending bar 48, the upper end of which fits against, and is welded to, the face of the block-like crosshead inner member 20 that is remote from the outer crosshead member 21. The upper end of the bar 48 is provided with an outwardly extending U-shaped bracket 49 and the lower end of said bar is provided with an outwardly extending U-shaped bracket 50. Preferably the inner ends of the side legs of the two brackets are welded to the side faces of the vertically extending bar 48. The upper end of the vertically extending piece 45 of the plow carrying bar 44 extends through the two brackets 49 and 50, as shown in Figure 1, and is held in place by a pair of set screws 51 and 52. The set screw 51 extends horizontally through the crosswall of the bracket 49 and is provided with a lock nut 53 for holding it in place. The other set screw, i. e., set screw 52, extends horizontally through the crosswall of the bracket 50 and has associated therewith a lock nut 54 for holding it in the different positions into which it is adjusted. A fulcrum member 55 is interposed between the central portion of the bar 48 and the adjacent por-

tion of the vertically extending piece 45 of the bar 44. This member is welded to the bar 48 and has the vertically extending piece 45 of the bar 44 clamped thereagainst by the set screws 51 and 52. When the set screws are loosened the plow 8 may be vertically adjusted in order to bring the lower or bottom edge thereof into proper position with respect to the bottom wall 11 of the lower section of the receptacle. Tightening of the set screws serves to hold the plow in fixed relation with the crosshead 6. By loosening one of the set screws and tightening the other set screw the plow may be tilted bodily in a vertical plane. In connection with tilting of the plow the vertically extending piece 45 of the bar 44 fulcrums on the fulcrum member 55 that is fixedly secured to the central portion of the bar 48. The two set screws 51 and 52 together with the fulcrum member 55 constitute means whereby the plow may be vertically adjusted and also tilted back and forth relatively to the crosshead 6. Ordinarily a tilting type adjustment of the plow is made only to compensate for any wear that should take place on the bottom edge of the plow. The position and arrangement of the bar are such that the leading or inner edge of the inner part 42 of the plow is at all times substantially in true alignment with the vertical center or axis of the receptacle 5.

In addition to the parts heretofore mentioned the apparatus comprises a scraper 56 for scraping the lower portion of the receptacle side wall. This scraper extends downwards and rearwards from the outer end of the outer part 21 of the crosshead 6 and has welded to its upper end an inwardly extending, horizontally disposed attaching arm 57. The latter overlies and extends longitudinally of the outer end of the web 23 of the crosshead member 21 and is secured in place by means of a pair of vertically extending bolts 58. Such bolts extend through holes 59 in the attaching arm 57 and slots 60 in the web 23. The slots permit the scraper to be adjusted inwards or outwards when the nuts on the bolts 58 are loosened.

When it is desired to use the apparatus to mull a batch of material the wheelbarrow 13, after release of the lower section 9 of the receptacle from the upper section 10, is wheeled to the location where the material to be mulled is stored. It is then charged with the material and wheeled back to a position wherein the lower receptacle section 9 is directly under the upper section 10. After properly positioning of the wheelbarrow the self contained mulling unit consisting of the upper receptacle section 10, the unidirectional electric motor 26, the speed reducing gearing 27, the crosshead 6, the wheels 7, the plow 8 and the scraper 56, is lowered until the ring 16 on the lower end of the side wall 15 rests on the ring 14 on the upper end of the side wall 12. Thereafter the electric motor 26 is started. As soon as the motor is started the crosshead 6 is set in motion and revolves within the receptacle 5. In connection with turning or swinging of the crosshead the mulling wheels 7 squeeze the material against the bottom wall 11 and the plow 8 plows the material outwards and deflects it into the path of the mulling wheels. After the material is mulled to the desired extent the aforementioned self contained unit is raised and the wheelbarrow is then wheeled to the location where the mulled material is to be used. In the event the bottom edge of the plow wears the plow is adjusted downwards by loosening the set screws 51 and 52 so as to release

the bar 44 from the U-shaped brackets 49 and 50. After downward adjustment of the plow to the proper extent fully to compensate for wear the set screws are tightened. Should the wear of the bottom edge of the plow be such as to necessitate tilting or angular adjustment of the plow the plow is angularly adjusted by loosening one of the set screws and tightening the other as heretofore pointed out.

10 The herein described mulling apparatus effectively and efficiently fulfills its intended purpose and is characterized by the fact that the plow 8 is so constructed and shaped that it operates on the entire batch of material in the receptacle.

15 Because of the design and construction of the crosshead the apparatus may be manufactured at a comparatively low cost.

20 Whereas the apparatus has been described as comprising a composite or sectional receptacle, the lower section of which is detachable from the upper section, it is to be understood that the invention involves the use of a rigid or unitary receptacle. It is also to be understood that the invention is not to be restricted to the details set forth since these may be modified within the scope of the appended claims without departing from the spirit and scope of the invention.

25 Having thus described the invention what I claim as new and desire to secure by Letters Patent is:

30 1. In a mulling apparatus comprising a bowl-like receptacle embodying a bottom wall and a continuous upstanding side wall and adapted to retain the material to be mulled, a rotary crosshead supported from above, positioned over and in spaced relation with the receptacle bottom wall, and provided with means for driving it in one direction, and a rotary mulling wheel carried by the crosshead and adapted during drive of the latter to travel in a circular course within the receptacle interior and effect mulling of the material by squeezing it against said receptacle, a horizontally elongated plow carried by and depending from the crosshead, positioned and arranged so that during drive of said crosshead it travels in a circular course over the receptacle bottom wall and deflects the material into the path of the mulling wheel, extending outwards from substantially the true center of the receptacle to the side wall, and horizontally and spirally curved in a direction opposite to the direction of drive of the crosshead and in such manner that its radius progressively and substantially uniformly increases from its inner end to its outer end, in order that any of the material that works its way to the center of the receptacle in connection with a mulling operation is positively moved outwards towards the receptacle side wall.

35 2. In a mulling apparatus comprising a bowl-like receptacle embodying a bottom wall and a continuous upstanding side wall and adapted to retain the material to be mulled, a rotary power driven crosshead positioned over and in spaced relation with the receptacle bottom wall, and a rotary mulling wheel carried by the crosshead and adapted during drive of the latter to travel in a circular course within the receptacle interior and effect mulling of the material by squeezing it against said receptacle, a horizontally elongated plow positioned beneath the crosshead and directly over the receptacle bottom, extending outwards from the central part of the receptacle to the side wall, having means between it and the crosshead whereby it is connected to rotate conjointly with the crosshead while at the same time

it is capable of being adjusted vertically and also tilted longitudinally, and adapted during drive of said crosshead to travel in a circular course over the receptacle bottom and deflect the material outwards into the path of the mulling wheel.

3. In a mulling apparatus, the combination with a bowl-like receptacle embodying a bottom wall and a continuous upstanding side wall and adapted to retain the material to be mulled, a rotary power driven crosshead positioned over and in spaced relation with the receptacle bottom wall, a rotary mulling element carried by the crosshead and adapted during drive of the latter to travel in a circular course in the receptacle interior and effect mulling of the material by squeezing it against said receptacle, of a horizontally elongated plow positioned directly over the receptacle bottom wall, extending outwards from the central portion of the receptacle to the side wall, and adapted in connection with drive of the crosshead to travel in a circular course and deflect the material into the path of the mulling wheel, and a substantially vertically extending attaching member having the lower end thereof connected fixedly to the inner end of the plow and having means between its upper end and the crosshead whereby it is so connected to the crosshead that it together with the plow is capable of being adjusted vertically and also tilted in a vertical plane extending radially with respect to the receptacle.

4. In a mulling apparatus, the combination with a bowl-like receptacle embodying a bottom wall and a continuous upstanding side wall and adapted to retain the material to be mulled, of a 35 rotary horizontally elongated power driven crosshead positioned over and in spaced relation with the receptacle bottom wall and comprising a horizontal web and a pair of laterally spaced side flanges connected to, and depending from, the side margins of the web, a horizontally extending pivot bolt connected to, and extending between, said side flanges, an arm disposed beneath and in substantially parallel relation with, the crosshead and having one end thereof connected to the pivot bolt so that it is capable of swinging vertically, a vertically extending bolt extending

between and through the arm and the web and serving to limit downward swinging of the arm, an axle extending transversely of the arm and having its central portion fixedly connected to the distal end of said arm, and mulling wheels mounted rotatably on the ends of the axle.

5. In a mulling apparatus, the combination with a bowl-like receptacle embodying a bottom wall and a continuous upstanding side wall and adapted to retain the material to be mulled, of a rotary horizontally elongated power driven crosshead positioned over and in spaced relation with the receptacle bottom wall and comprising a horizontal web and a pair of laterally spaced side flanges connected to, and depending from, the side margins of the web, a horizontally extending pivot bolt connected to, and extending between, said side flanges, an arm disposed beneath and in substantially parallel relation with, the crosshead and having one end thereof connected to the pivot bolt so that it is capable of swinging vertically, a vertically extending bolt extending between and through the arm and the web and serving to limit downward swinging of the arm, a spiral compression spring extending around the last mentioned bolt and between said arm and web and arranged to urge the arm downwards, an axle extending transversely of the arm and having its central portion fixedly connected to the distal end of said arm, and mulling wheels mounted rotatably on the ends of the axle.
